US00D347146S

United States Patent [19]**Harrison**[11] **Patent Number: Des. 347,146**[45] **Date of Patent: ** May 24, 1994**

- [54] **HANDLE FOR FLATWARE AND TOOTHBRUSHES**
- [75] Inventor: **Susan Harrison, Wichita Falls, Tex.**
- [73] Assignee: **Zooth, Inc., Wichita Falls, Tex.**
- [**] Term: **14 Years**
- [21] Appl. No.: **5,755**
- [22] Filed: **Mar. 11, 1993**
- [52] U.S. Cl. **D7/656; D4/107**
- [58] Field of Search **D7/642, 649, 651, 654, D7/656, 401.2; D4/104, 107, 124-126; 15/167.1**
